(57) **CLAIM**

The ornamental design for a packing label, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front perspective view of a packing label showing my new design; and,

FIG. 2 is a top plan view thereof.

The broken line showing of elements on the packing label is for the purpose of illustrating environment and forms no part of the claimed design.

**1 Claim, 2 Drawing Sheets
(2 of 2 Drawing Sheet(s) Filed in Color)**
